CURTAIN SUPPORTING DEVICE

Filed Nov. 10, 1931

Invictor:
Albert Ippi
by his Attorney
Howard Johnson

UNITED STATES PATENT OFFICE

ALBERT IPRI, OF PHILADELPHIA, PENNSYLVANIA

CURTAIN-SUPPORTING DEVICE

Application filed November 10, 1931. Serial No. 574,195.

This invention relates to supporting devices and particularly to devices for supporting curtain rods and shade rollers. The principal object of the invention is to provide a device of simple construction which can be manufactured at low cost and which is highly efficient in performing its intended function.

Another object of the invention is to provide an adjustable device which is adapted for attachment in various manners to a supporting structure such as a window frame, door, or the like.

Another object of the invention is to provide a device which is readily adjustable to adapt it for use with various sized curtain rods and shade rollers.

It is well known that successive occupiers of dwelling houses or the like continually mutilate the window frames, doors and like structures when attaching curtain rod and shade roller supporting devices to those structures. The commonly used type of supporting device merely comprises separate elements for supporting the ends of the curtain rods and shade roller, such elements being attachable to the supporting structure, such as a window frame, by screws, tacks or the like. These supporting elements must be moved to accommodate different sized curtain rods or shade rollers, resulting in the above-mentioned destructive mutilation of the woodwork. This practice is especially prevalent in the case of a leased dwelling where successive tenants have no interest in the landlord's property and have little hesitation in mutilating the same.

The present device eliminates entirely the above-mentioned destructive action since it may be attached to the window frame or like structure and remain there for use with different sized curtain rods or shade rollers. Furthermore, it eliminates the bothersome moving or mounting of the ordinary supporting elements. Even when removed or replaced, the present device is more readily attachable to the supporting structure than are the ordinary elements. The device is illustrated in detail in the accompanying drawings to which reference may be had in con-

nexion with the following detailed description for a complete disclosure. In the drawings:

Fig. 1 is a perspective view of the device which is illustrated in one mounting position thereof upon a window frame;

Fig. 2 is a partial detail view of one end of the device, illustrating the construction thereof and also illustrating an alternative manner of attachment to the window frame;

Fig. 3 is a sectional view along line 3—3 of Fig. 2;

Fig. 4 is a sectional view along line 4—4 of Fig. 1; and

Fig. 5 is a sectional view along line 5—5 of Fig. 2.

Referring to the drawings and particularly to Fig. 1, the device of the invention comprises a supporting member 1 which is preferably formed of wood and shaped to have an ornamental design such as is illustrated in the figure. This member may be painted the same color as the window frame or other structure to which it is attached. A two-part bracket assembly designated generally by reference character 2 is carried by supporting member 1. This bracket assembly comprises a pair of L-shaped brackets 3 and 4, the long arms of the brackets being disposed in overlapping relation, as clearly illustrated. The brackets are preferably formed of flat strips of metal bent in the desired fashion. A pair of metallic straps 5 and 6, shown more clearly in Figs. 2 and 3, are mounted in spaced relation upon supporting member 1, as illustrated in Fig. 1. These straps may be permanently fastened to the supporting member by means of screws, as shown in Fig. 3, and they are of such length that the bracket arms may extend slidably beneath them, the purpose of the straps being to act as supporting guides for the brackets. A flat strip 7 of thickness equal to that of strap 3 may be mounted on supporting member 1 beneath bracket 4 and strap 6 to properly space the bracket from the supporting member. A centrally disposed adjustable strap 8 is also mounted upon supporting member 1, which strap is shown in detail in Fig. 4. The lower end of this strap is perma-

nently secured to the supporting member by means of a screw or the like, while the upper end is apertured to slidably receive a threaded stud 9 permanently carried by and extending 5 from supporting member 1. An internally threaded knob 10 is carried upon the free end of stud 9 and serves to adjustably position strap 8 in proper clamping relation to the overlapping arms of brackets 3 and 4 which 10 extend beneath the strap. In addition to serving as an additional supporting guide for the brackets, strap 8 thus also serves as a clamp to firmly hold the brackets in the desired adjusted position.

15 Brackets 3 and 4 are disposed so that their short arms extend vertically downwardly from supporting member 1 and these arms carry curtain rod supporting studs 11, 12 and shade roller supporting studs 13, 14.

20 These studs are properly formed to accommodate the usual type of curtain rod and shade roller, the construction of which elements is well known. In Fig. 1, a pair of conventional adjustable curtain rods are illustrated by broken line representations. The supporting studs may be attached to the brackets in any suitable manner, such, for example, as by providing threaded apertures in the brackets and threaded extensions upon the studs for cooperation therewith, as illustrated in Fig. 3. Any other manner of attachment of these elements may be used.

In Fig. 1, the device of the invention is illustrated as being supported upon the top surface of a window frame, such frame and the associated structure being illustrated by a broken line representation. In this instance, a pair of holes 15 extend vertically through the supporting member and suitable screws, or like fastening elements, serve to rigidly attach the supporting member to the window frame. It will be apparent, of course, that the supporting member may be attached to the front surface of a window frame or to the back of a door near the top thereof by providing horizontally extending holes through the supporting member, through which screws or the like may be inserted for attachment purposes. In either of these manners of attachment, the supporting member may be permanently attached and used with various sized curtain rods and shade rollers by merely adjusting the brackets in an obvious manner.

55 In Fig. 2 there is illustrated a method of attaching the device to a window frame or like structure which, while capable of permanent attachment by screws or the like, may be practiced without such fastening means, 10 no mechanical connection to the window frame being required. The ends of supporting member 1 are provided with elongated recesses, only one of which 16 is shown on the drawings, it being understood that the construction of the device is similar at both ends, 15

A metallic internally threaded insert 17 is disposed within each of the recesses, as shown clearly in Fig. 5. A screw jack 18 having a threaded shank 19 and flange 20 is provided at each end of the supporting member. The threaded shank of each jack extends into the associated recess of the supporting member and is threadedly received by the metallic insert 17. The flange 20 of each jack is rotatably mounted upon the end of shank 18 by means of a suitable screw. Each flange is provided with openings 21 for the reception of fastening screws or the like which may or may not be used. 70 75

It will be obvious that when the device is used, as in Fig. 1, the screw jacks may be entirely removed from the supporting member. In the event that it is desired to attach the device to the inner surface 22 of a window frame, as illustrated in Fig. 2, the screw jacks may be cooperatively associated with the supporting member and may be adjusted by turning their respective shanks with a suitable gripping tool, while the device is held in centrally located position, until the flanges 20 press firmly against and frictionally engage the inner surfaces of the window frame. The reason for having the flanges of the jacks rotatable with respect to the shank is to eliminate rotation of the flanges with the shanks while the flanges are in engagement with the window frame surface, thereby eliminating scratching of such surface due to rotation of the flanges. If desired, the flanges may be permanently secured to the window frame by means of screws or the like, but the jacks are purposely provided for the attachment of the device free of mechanical connection to the window frame. If desired, the outer surface of the jack flanges may be provided with suitable cushion means, such as a layer of felt or the like so as to further prevent scratching or marking of the window frame. When used as in Fig. 2, the device must, of course, be shorter than the distance between the opposite inner surfaces of the particular window frame.

It will be apparent that the device of the present invention is novelly constructed, as described and illustrated, to provide a simple device which is capable of flexibility of use to meet the various needs of different users. The present disclosure is, of course, for the purpose of illustration only and any such changes or modifications as come within the scope of the appended claims are deemed to be within the scope of the invention. 115 120

I claim:

1. A device of the class described, comprising a supporting member, means for removably attaching said member to a supporting structure, and adjustable means carried by said supporting member for supporting different sized curtain rods and shade rollers, said last means comprising a pair of slidable 130

flat L-shaped brackets having overlapping arms, the other arms of said brackets extending downward from said supporting member and carrying supporting studs for a curtain rod and a shade roller.

2. A device of the class described, comprising a supporting member, a pair of spaced stationary guide straps and a central adjustable guide strap mounted on said member, means for removably attaching said member to a supporting structure, and adjustable means carried by said supporting member for supporting different sized curtain rods and shade rollers, said last means comprising a pair of flat L-shaped brackets having overlapping arms slidably carried by said guide straps, the other arms of said brackets extending downward from said supporting member and carrying supporting studs for a curtain rod and a shade roller.

3. A device of the class described, comprising a supporting member, means for attaching said supporting member free of mechanical connection to a window frame, and means carried by said supporting member for supporting a curtain rod and a shade roller.

4. A device of the class described, comprising a supporting member, means for attaching said supporting member free of mechanical connection to a window frame, said means comprising extensible jacks carried at the ends of said supporting member and adapted to frictionally engage the inner surfaces of said frame, and means carried by said supporting member for supporting a curtain rod and a shade roller.

5. A device of the class described, comprising a supporting member having recessed ends, means for attaching said supporting member free of mechanical connection to a window frame, said means comprising extensible jacks carried in the recessed ends of said supporting member and adapted to frictionally engage the inner surfaces of said frame, and means carried by said supporting member for supporting a curtain rod and a shade roller.

6. A device of the class described, comprising a supporting member, screw jacks carried at the ends of said member for attaching the same to the inner surfaces of a window frame, and means carried by said supporting member for supporting a curtain rod and a shade roller.

7. A device of the class described, comprising a supporting member having recessed ends, screw jacks carried in the recessed ends of said member for attaching the same to the inner surfaces of a window frame, and means carried by said supporting member for supporting a curtain rod and a shade roller.

8. A device of the class described, comprising a supporting member having recessed end and screw threaded inserts therein, screw

jacks threadedly carried by said inserts in the recessed ends of said member for attaching the same to the inner surfaces of a window frame, and means carried by said supporting member for supporting a curtain rod and a shade roller.
